TEMPERATURE CONTROL DEVICE FOR
FURNACES

Robert M. Baker, Toledo, Ohio

Application August 23, 1934, Serial No. 741,122

7 Claims. (Cl. 236—104)

This invention relates to temperature control devices for furnaces, but particularly to an automatic device for controlling one or more dampers in accordance with the heat generated by the furnace.

An object of this invention is to produce a new and improved furnace temperature control or regulator, which can be initially or from time to time adjusted in a simple manner to the temperature desired, and will thereafter operate automatically to obtain a substantially uniform temperature of a predetermined degree. Another object is to produce a furnace temperature regulator which has the novel features of construction, operation and arrangement hereinafter described.

Further objects and advantages will hereinafter appear, and, for purposes of illustration, an embodiment of the invention is shown on the accompanying drawings, in which:

20 Figure 1 is a fragmentary side elevational view of a furnace with a portion of the casing and body of the furnace broken away to show the interior thereof equipped with my new temperature regulator;

25 Figure 2 is a transverse sectional view on the line 2—2 of Figure 1 showing the baffle construction of the smoke consumer;

30 Figure 3 is an enlarged sectional view on the line 3—3 of Figure 1 showing the thermally actuated rocking bar;

Figure 4 is a sectional view on the line 4—4 of Figure 3;

35 Figure 5 is an enlarged fragmentary front elevation of an upper end portion of the furnace casing showing the manual control for the thermally actuated bar; and

Figure 6 is a fragmentary side elevational view of the upper end of the furnace casing showing the blower control.

40 The illustrated embodiment of the invention comprises a furnace body or shell 10 of the usual steel construction, or of such material, as to expand or contract thermally, and enclosing the body 10 is a casing or jacket 11 of sheet metal, or other suitable material.

45 Mounted on the upper end of the furnace body is a pointed fulcrum 12 on which rests a lateral extension 13 of a bar 14, which extends transversely of the upper portion of the casing 11. The lateral extension 13 is preferably disposed centrally of the bar 14 and the bar is rockable in response to thermo-expansion or contraction of the furnace body 10. The opposite ends of the bar 14 are considerably reduced in size and are rounded, one 55 end being rockably mounted in a plate 15 having

a stud 16 suspended from a bracket 17, a nut 18 adjustably holding the plate 15 in the desired position. Initially, the vertical position of the plate 15 is adjusted by turning the nut 18.

The opposite rounded end of the bar 14 is 5 mounted in and free to rock relative to one end of an adjusting arm 19. The arm 19 is pivoted at 20 in an embossed portion of a bracket plate 21, which is secured to the outside of the casing 11. The opposite end of the arm 19 extends outside of 10 the casing 11 through a vertically elongate slot 22. Extending laterally from the arm 19 is a flange or tooth 22a which may be moved into selective engagement with one of the notches 23 on a calibrated indicator plate 24. It will be noticed 15 that this plate is calibrated from zero to seventy degrees, and the arm 19 is adjusted with respect to this plate in accordance with the temperature of the air outside of the building. For example, if the outside temperature is 25° F. the arm 19 20 is adjusted so that the tooth 22 is inserted in the notch corresponding to the 25° calibration on the plate 24, and, as will hereinafter appear, this adjusts the thermally actuated bar 14 properly to 25 maintain a suitable temperature within the room 25 to compensate for the cooler outside temperature.

Fixed to the bar 14 between the lateral extension 13 and one end of the bar, is an arm 25 to the outer end of which is pivoted a depending link 26. The lower end portion of the 30 link 26 is provided with a series of holes 27 selectively to receive a bolt for connection to an arm 28, the inner end of which is provided with a weight 29. The opposite end portion extends through the case 11 and is pivotally mounted at 30, and the free end thereof is connected by a chain 31 to a draft damper 32 of the usual form disposed at the lower part of the furnace, in this instance being mounted on the door 33 35 of the ash pit. The arm 28 is also connected 40 by a slotted link 34 to a door 35, which controls the passage 36 leading to a vertically disposed bell-shaped smoke consumer 37 in which is disposed a core 38 having a series of radial baffles 45 or blades 39 suspended in place by a bolt 40.

It will be understood that when the door 35 is open, air is drawn therethrough and broken up by the baffle plates 39 to effect more complete combustion of fuel within the combustion chamber. It will be understood that the weight 29 is sufficient substantially to compensate for the weight of the dampers 32 and 35 in order to maintain substantially a balanced condition and to enable slight vertical movement of the arm 55

26 to effect the desired opening or closing movement to these dampers.

If desired, a blower may be provided for forcing air through the furnace, and thereby increase the circulation of air through the furnace. Such blower is not shown on the drawings, but any well known type of electrically driven blower may be used for this purpose and may be operated by an arm 41, which is fixed at one end 5 to the end of the bar 14 adjacent the bracket plate 15. The opposite end of the arm 41 may be L-shaped and is formed with a looped end to engage a switch arm 42. Upon rocking movement of the arm 14 in one direction, the arm 15 41 will be moved in such manner as to move the switch arm 42 to close an electric circuit for energizing the blower, and actuation in the opposite direction will move the switch arm 42 to open the blower circuit.

20 In operation it is apparent that the expansion or contraction of the furnace body 10 operates to rock the bar 14, and this movement is transmitted by links and levers to the doors 32 and 35, which may be concomitantly opened or 25 closed to increase or diminish the draft to the combustion chamber. The amount of such movement, it is apparent, is controlled by the adjustment of the control arm 19, and such adjustment is dependent upon the outside temperature.

30 It is to be understood that the above description is to be given by way of illustration and not of limitation, and numerous changes in details of construction and operation may be effected without departing from the spirit of the 35 invention, especially as defined in the appended claims.

What I claim as new and desire to secure by Letters Patent is:

1. A temperature controlling device for a furnace provided with a furnace body, a housing enclosing said body and a draft damper, said device comprising a fulcrum on the top of said body responsive to thermal expansion or contraction of said body, a bar extending across said housing, a pivotal mounting for opposite ends of said bar enabling axial turning movements thereof, a lateral extension on an intermediate portion of said bar resting on said fulcrum, lever and link means connecting said bar with said damper for actuating same upon turning movements of said bar, and means for raising or lowering one end of said bar for predetermining the action thereof.

2. A temperature controlling device for a furnace provided with a furnace body, a housing enclosing said body and draft damper, said device comprising a fulcrum on the top of said body responsive to thermal expansion or contraction of said body, a bar extending across said housing, a pivotal mounting for opposite ends of said bar, a lateral extension on an intermediate portion of said bar resting on said fulcrum, lever and link means connecting said bar with said damper for actuating same upon rocking movements of said bar, an arm pivoted adjacent one end and engaging said bar at such end, the opposite end of said arm extending outside of said housing to enable same to be adjusted for predetermining the action of said bar.

70 3. A temperature controlling device for a furnace provided with a furnace body, a housing

enclosing said body and a draft damper, said device comprising a fulcrum on the top of said body responsive to thermal expansion or contraction of said body, a bar extending across said housing, a pivotal mounting for opposite ends of said bar, a lateral extension on an intermediate portion of said bar resting on said fulcrum, lever and link means connecting said bar with said damper for actuating same upon rocking movements of said bar, an arm pivoted adjacent one end and engaging said bar beyond the pivotal point thereof, the free end of said arm extending outside of said housing, a plate on said housing calibrated in degrees of temperature, and means on said plate for receiving the free end of said arm in selective position.

4. A temperature controlling device for a furnace provided with a furnace body, a housing enclosing said body and a draft damper, said device comprising a fulcrum on the top of said body responsive in vertical movement to changes in thermal conditions of said body, a bar extending across said housing, a pivotal mounting for opposite ends of said bar enabling axial turning movements thereof, a lateral intermediate extension on said bar resting on said fulcrum, and lever and link means connecting said bar with said dampers for actuating same from turning movements of the former.

5. A temperature controlling device for a furnace provided with a furnace body, a housing enclosing said body and a draft and smoke consumer dampers, said device comprising a fulcrum on the top of said body responsive to thermal expansion and contraction of said body, a bar extending transversely of said housing, a mounting for opposite ends of said bar to afford axial turning movements thereof, a lateral extension on said bar resting on said fulcrum, and operative connections between said bar and dampers to actuate same from rocking movements of the former.

6. A temperature controlling device for a furnace provided with a furnace body, a housing enclosing said body and a draft damper, said device comprising a fulcrum on the top of said body responsive in vertical movement to changes in thermal conditions of said body, a bar extending across said housing, a mounting for opposite ends of said bar to afford turning movements thereof, a lateral intermediate extension on said bar resting on said fulcrum, and lever and link means connecting said bar with said dampers for actuating same from turning movements of the former, said lever and link means including a counterbalance for said damper.

7. A temperature controlling device for a furnace provided with a furnace body, a housing enclosing said body, a draft damper and an electric blower control, said device comprising a fulcrum on the top of said body responsive to thermal expansion and contraction thereof, a bar extending transversely of the upper end of said housing, a mounting for said bar affording axial rocking movements thereof, a lateral intermediate extension on said bar resting on said fulcrum, and lever and link means operatively connecting said bar and said damper and electric blower control for actuating the latter from rocking movements of the former.

70 ROBERT M. BAKER.
